UNITED STATES PATENT OFFICE

92,416

DESIGN FOR AN AQUARIUM

William E. McCormick, New York, N. Y., assignor
to Jerome S. Hilborn, New York, N. Y.

Application July 11, 1933, Serial No. 48,686

Term of patent 7 years

To all whom it may concern:

Be it known that I, WILLIAM E. McCORMICK, a citizen of the United States, a resident of New York, Borough of Bronx, county of Bronx, and State of New York, have invented a new, original, and ornamental Design for Aquariums, of which the following is a specification, reference being had to the accompanying drawing, forming a part thereof.

In the drawing:

Figure 1 is a view in front elevation of an aquarium embodying my improved design; and

Fig. 2 is a view in section taken on the line 2—2 of Fig. 1.

As shown in the drawing, the aquarium consists of a drum shaped casing 10 with a front wall 11 of glass surrounded by an annular frame 12. The latter is formed with bolt heads 13 so as to give the appearance of a port hole.

I claim:

The ornamental design for an aquarium as shown and described.

WILLIAM E. McCORMICK.
